UNITED STATES PATENT OFFICE.

MINAS H. KASHIAN, OF AMESBURY, MASSACHUSETTS.

COMBINATION CUTUNDER CARRIAGE.

SPECIFICATION forming part of Letters Patent No. 745,108, dated November 24, 1903.

Application filed July 24, 1903. Serial No. 166,919. (No model.)

To all whom it may concern:

Be it known that I, MINAS H. KASHIAN, of Amesbury, in the county of Essex and State of Massachusetts, have invented new and useful Improvements in Combination Cutunder Carriages, of which the following, taken in connection with the accompanying drawings, is a specification.

The object of this invention is to provide simple, convenient, durable, and satisfactory means for promptly converting a single-seated into a two-seated vehicle, or vice versa, at will, without removing either of the seats therefrom or making any part of the vehicle unsightly.

To this end my invention consists in the construction and combination of parts hereinafter set forth and claimed.

In the accompanying drawings, Figure 1 represents a side view of the vehicle with both seats in place and ready for four occupants. Fig. 2 represents a similar view of the same arranged for two passengers only, the rear seat having moved forward and the former front seat dropped, as shown by dotted lines. Fig. 3 represents a transverse vertical section on a plane just in front of the bars J, belonging to the rear seat D. Fig. 4 represents a similar view of a part of one side of the rear seat and body enlarged. Fig. 5 represents a transverse vertical section taken just in front of the bars I, belonging to the front seat C. Fig. 6 represents a detail perspective view from within of one of the panels K and adjacent parts.

A designates the bottom of the vehicle-body; B, its sides; C, the front seat, having a forward-folding back C', hinged at c, and D the rear seat. The front seat has on opposite sides, near its bottom, two laterally-extending studs C², which may project from the ends of a transverse bar or plate C³, as shown in Fig. 6, one stud being near each corner and entering a groove I' of an upright supporting plate or bar I, attached to the bottom or one of the sides of the vehicle-body aforesaid. Each of these grooves is for the most part vertical, but has a rearwardly-turned upper end i. When the seat C is in use, as shown in Fig. 1, the studs are at the rearward ends of these horizontal extensions i, so that the weight of the seat comes on these supporting

plates or bars I; but when it is desired to lower the seat C it is pulled forward until the said studs pass into the vertical parts of the grooves. The seat may then be pressed down against the resistance of springs II, interposed between it and the bottom of the vehicle-body. A catch E, attached to the wagon-body, holds the seat against rising above the level of the sides B. Each of these sides is provided on top with a guideway F, consisting of a longitudinal groove or recess covered by a longitudinally-slotted plate. This guideway is interrupted in the middle, when the seats are arranged as in Fig. 1, by a long and deep depression or recess G, where the middle of each side is cut away. A shield or panel K on each side of the front part of the said body is connected to the proximate side B by a hinge g at its lower rear corner and provided along its upper edge with a guideway F' when the said shield or panel is turned over backward on its hinge into the said recess. A catch of any convenient form holds it down. While these panels are in their higher forward position (shown in Fig. 1) they protect the supporting-bars I and springs H and screen them from view. When in their lower rearward position, they give the carriage-body a more finished appearance than it otherwise could have and adapt it to carry articles along the whole length of that part of it behind the front seat.

The rear seat D has downwardly-extending bars J attached to it near its corners, the lower end of each of the said bars being provided with a head j, extending into the guideway F and under the upper plate thereof at the sides of its longitudinal slot, through which the said rod passes, the said bars constituting the only means of attachment of the said seat D to the wagon-body. When the rear seat D is moved forward, the heads, arms, or hooks j slide into the guideway F' of panel G, and thence into the forward part of the guideway F until the rear seat D comes over the front seat C, previously lowered, as described, after folding down the back C', and so takes its place, being then the only seat of the vehicle in position for use. The vehicle is then adapted to be used by two persons only, its rear part being available for baggage, parcels, or any articles which there

may be need to carry. The front end of each panel K is then held down by a pivoted catch O, hooking under a stud below it on the inner face of the side of the wagon-body. When it is desired to convert it into a two-seated vehicle again, the procedure is reversed, the seat D being moved back into its rearward place, the panels I being freed and turned over forward into the position shown in Fig. 10 1, the catch E freed, permitting the springs H to raise the seat C, and the studs C² being moved along into the rearward horizontal extensions i of the grooves I', so that the bars I support the seat C again, and the back C' 15 is turned up, as usual. If it should be accidentally jostled forward, bringing the studs over the vertical parts of the said slots, the springs H will cushion its fall; but the studs are made to fit the grooves closely enough to 20 prevent this accidental displacement in any ordinary circumstances, and the backward pressure of the weight of the occupants of the seat will assist in holding it in place.

The rear seat is provided with a downwardly-extending casing K, which always protects the bars J and also protects the bars I when said seat is moved over the lowered front seat.

Having thus described my invention, what 25 I claim as new, and desire to secure by Letters Patent, is—

1. In combination with a vehicle-body having cut-away sides, a front seat adapted to descend within the said body, a rear seat 30 adapted to slide over the same, and movable panels adapted to protect the space below the front seat when it is in use and to fill the recessed or cut-away parts of the sides at will substantially as set forth.
2. In combination with a vehicle-body having cut-away sides, a front seat, supporting devices for the front seat permitting it to descend at will, panels hinged at their rear lower corners to the sides of the body and protecting 35 said supports when the said seat is in use, but adapted to turn over back and fill the recesses of the said cut-away sides, and a rear seat adapted to slide over the lowered front seat for the purpose set forth.
3. In combination with a vehicle-body having cut-away sides and guideways F, a rear seat provided with downwardly-extending bars engaging the said guideways, a front seat adapted to be lowered within the said

body, and reversible panels hinged to the 55 said body and provided with guideway-sections F', which complete the guideway, to permit the rear seat to slide over the lowered front seat, the said panels protecting the supporting devices of the front seat when the latter is in position for use and the said panels are turned forward substantially as set forth.

4. In combination with a vehicle-body, a seat provided with lateral studs, supports provided with upright grooves receiving the 60 said studs and bent horizontally at their upper ends and a spring or springs tending to replace or support the said seat substantially as set forth.

5. In combination with a cut-away vehicle- 70 body, a seat provided with lateral studs, supports provided with upright grooves receiving the said studs and bent horizontally at their upper ends, a spring or springs for replacing and aiding in supporting the said seat, panels for protecting the said springs and supports, but movable to fill out the cut-away parts of the sides of the vehicle-body and a rear seat adapted to slide forward over the front seat after the latter is lowered substantially as set forth.

6. In combination with a vehicle-body, a spring-supported front seat adapted to be lowered within the same, a rear seat adapted to slide over the front seat when thus lowered, and hinged panels, which may be turned at will into position to protect the said springs, or to fill the recesses in the cut-away sides, substantially as set forth.

7. In combination with a cut-away vehicle- 90 body, a front seat adapted to be lowered within the same, supporting devices for the said seat, hinged panels protecting such devices, but adapted to be turned into position to fill out the cut-away parts of the sides instead, and a rear seat adapted to slide forward over the said front seat when the latter is lowered, the said rear seat being provided with an attachment for protecting the said supports substantially as set forth.

In testimony whereof I have signed my name to this specification, in the presence of two subscribing witnesses, on this 18th day of July, A. D. 1903.

MINAS H. KASHIAN.
